UNITED STATES PATENT OFFICE.

JOHN W. BASKERVILLE, OF BAYONNE, NEW JERSEY.

RAILWAY-CAR.

1,266,387.

Specification of Letters Patent. Patented May 14, 1918.

Application filed June 12, 1917. Serial No. 174,379.

To all whom it may concern:

Be it known that I, JOHN W. BASKERVILLE, a citizen of the United States, residing at Bayonne, in the county of Hudson 5 and State of New Jersey, have invented new and useful Improvements in Railway-Cars, of which the following is a specification.

This invention relates to railway cars of 10 that kind comprising a body open at the top and adapted to contain coal, gravel or other material, and having a bottom provided with sloping surfaces and one or more doors through which the material may discharge by gravity down said sloping surfaces when the door or doors are open.

The object of the invention is to provide 15 a construction for a car of this character which will be an improvement over the construction disclosed in my U. S. Patent, No. 1,179,266, issued April 11, 1916, and to provide a car having swinging side doors whereby the contents of the car may be dumped from either or both sides in a ready, convenient and expeditious manner.

A further object of the invention is to provide an improved construction of freight car with sloping bottom surfaces, combined with a novel construction of pivotally 20 mounted side doors, and means for locking the side doors in closed position.

A still further object of the invention is to provide removable partitions whereby the interior of the car may be divided into 25 compartments, and also to provide auxiliary doors in the main doors whereby small portions of the contents of any of the compartments may be discharged at any time.

The invention consists of the features of 30 construction, combination, and arrangement of parts hereinafter fully described and claimed, reference being had to the accompanying drawings in which:

Figure 1 is a fragmentary side elevation 35 of a self-dumping freight car embodying my invention.

Fig. 2 is an end elevation of the same.

Fig. 3 is a fragmentary top plan view.

Fig. 4 is a vertical transverse section 40 through Fig. 1.

Fig. 5 is an enlarged detail sectional view showing one of the doors held open by the prop thereon.

Fig. 6 is an enlarged detail sectional view 45 on the line 6—6 of Fig. 1.

Referring to the drawings, 1 designates

the frame of the car body, including the sills 2, uprights 3, upper longitudinal side bars 4, cross bars 5, and fixed end walls 6, all of which parts are preferably formed of metal bolted or riveted together and suitably stayed and reinforced at proper points. 60

In accordance with my invention, the bottom of the car body, which is of the usual oblong rectangular form, is formed 65 by sloping walls 7 and 8 terminating at their outer edges in angularly bent portions forming inwardly extending horizontal flanges 9, which walls slope from the longitudinal center of the car body and form 70 downwardly and outwardly inclined planes on opposite sides of the longitudinal center of the car.

The walls 7 and 8 rest upon inclined transverse bars 10 which are stayed by suitable 75 angle braces 11 and 11' connected with plates 12 and 12'. The upper longitudinal side bars 4 are in the form of L-beams, having their short webs or flanges 13 horizontally arranged at their upper edges and 80 their longer webs or flanges 14 depending vertically. The sides of the car are formed by lower longitudinal side bars 15, also having their short webs or flanges 16 horizontally arranged at their upper edges and 85 their longer webs or flanges 17 depending vertically, said bars 15 being disposed at or near the horizontal longitudinal center of the wall and being connected with the uprights 3 and by other uprights 18 with 90 the bars 4, plates 19 being secured to said bars and uprights to close the spaces between the same and form a permanently 95 closed wall forming a rigid upper half of each side of the car. The parts 15 and 18 are also made of angle metal, and all the parts mentioned are bolted, riveted or otherwise firmly united together.

The lower half of each side wall of the car is formed of a series of swinging doors 100 20, each preferably comprising a sheet metal plate secured to angle metal end bars 21 and angle metal intermediate bars 22, the said end bars 21 being arranged adjacent the end edges of the door plate and the bars 105 22 between the bars 21 and the vertical center of the door plate. These angle bars 21 and 22 have apertured upper ends 23 serving as hinge straps which pivotally engage loops 24 secured to the vertical and horizontal webs of the beams 17. The doors are 110 provided at their upper edges with bracing

lips 25, and at their lower edges are provided with hollow beams, or strips 26 which are substantially triangular shape in cross section, the lower webs of which are inclined to conform to the inclination of the surfaces 7 and 8, whereby when the doors are fully closed the lips 25 will rest against the bars 15 and the beams 26 will bear against the sloping surfaces 7 and 8 thus effecting a 10 tight closure of the doors, the lips 25 also serving to reinforce the doors against the pressure of the material at the hinge points. In practice, the doors are arranged so as to be equal in number on each side of the vertical center of the car, and said doors may close bins, bays, or compartments formed by the sloping bottom walls together with suitable vertical transverse partitions, as hereinafter described. It will be observed that 20 while the lower portion of each side wall is formed of swinging doors, sufficient in number to easily and conveniently effect the discharge of the load, the upper half of each side wall constitutes a permanent rigid portion of the car body, thus making the body strong, rigid and durable at all points.

The horizontal flanges 9 at the lower edges of the walls 7 and 8 rest upon and are bolted or riveted to the upper horizontal webs of 30 the sills 2, the angular construction of the walls 7 and 8 at these points making a connection which is of maximum strength and durability. As shown, the walls 7 and 8 and their flanges 9 are provided with openings which register with openings in the upper webs of the sills 2, said openings being adapted to receive the lower ends of intermediate locking bolts 27 which are fitted to slide in guides on the intermediate angle 35 bars 22. These intermediate bolts may be employed to hold the individual doors closed while others are opened, and to also serve as means for bracing and reinforcing the doors against the pressure of the load. End 40 locking pins or bolts 28 are also provided upon the sills 2, and are vertically slidable through guide openings in the webs of said sills and in the plates 7 and 8 and their flanges 9, the upper ends of said bolts being 45 adapted for projection to engage the end angle metal bars upon each door for locking the door in closed position and also reinforcing the same against pressure of the weight of the load. The bolts 28 have rack teeth 50 meshing with gears 30, and the gears associated with the bolts between the center end of each side of the car are mounted upon an actuating shaft 30' which is journaled in suitable bearings upon the adjacent sill and 55 provided at its outer end with a weighted handle or lever 31 by means of which the bolts may be simultaneously retracted. Thus it will be understood that the intermediate bolts of one or more doors may be 60 individually released and the end locking

bolts of all the doors of one set simultaneously released, so that one or more doors may be opened while the others are held closed or all the doors opened, as desired. The weight upon the lever 31 serves to automatically maintain the end locking bolts in locking position by gravity without the use of additional retracting means. Each door is preferably provided with a pivotally mounted prop 32 provided with a manipulating handle 33 and which may be engaged with rack teeth 34 on the surface 7 or 8 to hold the door open to the desired angle necessary.

It will be understood that the load contained in the car rests upon the inclined bottom walls 7 and 8, and that by simply releasing either door or both doors the material at either side of the car or both sides of the longitudinal center of the car may be 80 discharged by gravity, the weight of the load forcing the doors open and the load then discharging down the inclined surfaces 7 and 8, as will be readily understood. When the load is discharged the doors swing back 90 to closed position by gravity and may be relocked by means of latches 27 in a ready and convenient manner. By the described construction of side-dumping car of the self-dumping type, it will be obvious that 95 the load may be dumped in a ready, quick and convenient manner, and with a minimum amount of time and labor on the part of the operator.

For the purpose of dividing the interior 100 of the car into any desired number of compartments, which may be equal in number to the opposed sets of side doors, I may employ vertical transverse partition plates 35 fitted to slidably mounted frames formed 105 from angle bars 36; and for the purpose of enabling the material of any compartment to be partially discharged, without opening the main door, I may provide each of the main doors with a small auxiliary door 37, 110 which may be held closed by any suitable form of latch device, and through which portions of the material may be discharged into wheel-barrows or other small receptacles when desired.

Having thus described the invention, what is claimed as new, is:

1. A self-dumping car including channeled side beams, upright end walls, pivotally mounted side doors having perforated 120 flanges at their lower ends, sloping bottom walls provided at their outer edges with angularly bent portions providing inwardly extending flanges resting upon the upper flange of the channeled beams, said walls, 125 flanges and channel flanges being provided with perforations to coincide with the first-named perforated flanges when the doors are closed, end latches upon the end walls to engage the end portions of the doors, and in- 130

termediate bolts upon the doors movable through the perforated flanges thereof and into engagement with the perforations in the sloping walls and side beams.

5 2. A self-dumping car including a side wall formed of a sill beam, an upper longitudinal bar, an intermediate longitudinal bar, uprights between said bars, sheet metal plates inserted between the bars and uprights and secured thereto and forming a closed wall above the longitudinal horizontal center of the car side, doors pivotally suspended from the lower bar and provided with angle metal uprights, bolts carried by 10 said uprights to engage the sill, and bolts

carried by the sill to engage and lock the doors.

3. A car having a side wall including a sill, a wall proper provided with openings, and pivoted doors for closing said openings, locking bolts slidably engaging the flanges of the sill to engage and lock the doors in closed position, said bolts being provided with gear teeth, a longitudinally extending shaft, gears upon said shaft to engage the 20 gear teeth of the bars, and an operating device attached to the shaft.

In testimony whereof I affix my signature.

JOHN W. BASKERVILLE.
